UNITED STATES PATENT OFFICE.

FRANK MUNHOLLON, OF CLEVELAND, OHIO.

HEAT-CONSERVING SYSTEM.

Application filed March 28, 1923. Serial No. 628,257.

My invention relates to a heat-conserving system adapted for use with pottery kilns and the like, and has for its object the provision of a method and means for operating 5 kilns, furnaces and the like in a more economical manner than obtains at the present time.

My improvements will be explained and described in connection with a plurality of 10 associated pottery kilns adapted for co-operative successive firing, or concurrently as a battery of kilns wherein the heat from the chimney stacks is returned to the system either for preheating a cooler kiln or for 15 assisting the firing of any particular kiln or kilns of the group or battery.

I may best describe my improvements in connection with the typical installation of a pottery kiln of well known type adapted 20 for firing by solid fuel, as shown in the accompanying drawings, wherein:

Figure 1 is a vertical sectional view of a pottery kiln equipped with my improvements,

25 Fig. 2 is a transverse view thereof on line 2-2, Fig. 1, and

Fig. 3 is a somewhat diagrammatic view illustrating my improvements as specifically applied to a group or battery of three 30 such pottery kilns as adapted for co-ordinated and economical firing.

Throughout the several figures of the drawings I have employed the same character of reference to indicate similar parts.

35 It is well understood that in the operation of kilns or other appliances requiring high degrees of heat there is required a considerable expenditure and relative waste of such heat in bringing the firing chamber to the 40 desired operative temperature. Moreover, in firing structures of this general class, it is recognized that large losses of heat are incurred through the normal functioning of the chimney stacks. Accordingly, it is my 45 purpose, as will be apparent from the explanation of my improvements, to overcome these wastes and losses in large measure and generally improve and control firing conditions.

50 A kiln *a* having a plurality of grates *b* for heating its firing chamber *c* (Fig. 1) is best shown in Fig. 2 with a system of piping *d* positioned in the chimney stack *e* immediately above the perforated arch *c'*. This piping 55 is shown in Fig. 1 as connected from but one of the eight inlets from header *f*,

merely for the sake of disclosing the preferred installation for the kiln in question for uniting each inlet to its corresponding outlet to the lower or hot air header *g*. 60 Pipes *g'* are connected from the hot air header to valve-controlled outlets *g'', g'*, respectively above and below the grates *b* of the eight peripherally disposed furnaces provided for heating the firing chamber *c*. 65 It may be explained that the illustration of the piping in the chimney stack, as well as the connecting headers and exterior piping, is purposely made of somewhat diagrammatic character merely for the sake of 70 clearness, since the details are of relatively minor importance.

The *O*-shaped headers *f* and *g* are respectively connected to mains *h* and *i*; the former being provided with a connection *h'* to a 75 blower (not shown) for supplying air to the main, or other suitable heat-conveying medium may be supplied to the system. Suitable control valves *j'', h''* are interposed between the mains and headers, so that the 80 heat-conveying medium may be directed throughout the system in accordance with current working conditions. For the purposes of this explanation, we may term the inlets as the cold air main and header and the exits or outlets as the hot air main and header for each of the combustion or firing chambers shown.

When one of the combustion chambers has been fired by lighting some or all of its fire 90 places or furnaces, and a temperature approximating 500° F. has been established therein, the system of pipes *d*, positioned above the perforated arch and partially protected from the direct action of the heated 95 gases, will necessarily take up a considerable portion of the excess or otherwise wasted heat. Accordingly, a circulation of air is established from the cold air main and header and this heat may be advantageously returned to the firing chamber *c* from the hot air header through the pipes *g'* and outlets *g'', g'*, above and below the grates *b*. It is apparent that solid fuels need not be used, but other fuels may be substituted therefor 100 and burned in conjunction with the hot air supply as above explained, if it be so desired.

In the event that another firing chamber is to be started, a material conservation of fuel 116 and heat may be effected by directing the heat-conveying medium from the hot air

main i to its corresponding header g of an adjacent firing chamber, as from chamber A, assumed to be the one under firing conditions, to chamber B or C (Fig. 3), which is assumed to be ready for firing. On the other hand, the hot air may be diverted for any other industrial purpose through the outlet pipe i' , if it be so desired, instead of partially heating another firing chamber, as above explained. It will be appreciated that greater adaptability is insured for a system equipped and operating as above explained, for the reason that the heated air may be employed as conditions require from time to time, both as a supporter of combustion in preheated condition to return the heat to the furnace being fired and to preheat adjacent combustion chambers at one and the same time. This secures economies in operation and insures the largest possible supply of heated air, as compared with a system incapable of thus distributing the heat-conveying medium, or one relying solely upon the diversion of the highly heated gases from the stack.

In order to protect the system of piping d in the event the blower accidentally stops or if the air supply is inadequate, I have provided a connection for steam or water at j , controlled by the valve j' , whereby the pipes may be protected against excessive heating. Moreover, I also provide a vent valve k , which may be opened to permit the escape of air or vapors from the pipes d .

Having now set forth apparatus explanatory of my invention and its preferred mode of operation as typical of my improvements, I claim as new and desire to secure by Letters Patent, together with such modifications as may be made by mere skill, the following:

1. The herein described method of operating a plurality of firing chambers, which consists in firing one of said chambers, directing an unvitiated combustion-supporting heat-conveying medium through said chamber to preheat its air supply and to an adjacent firing chamber, whereby the excess or waste heat in the first-named firing is availed of partially to heat the second firing chamber, substantially as set forth.

2. The herein described method of conserving heat in a battery of firing chambers, which consists in firing one of said chambers and directing air currents through said chamber to afford a preheated supply of air for combustion and to another firing chamber in unvitiated condition, whereby the heat from the first-named chamber may be employed partially to heat the second firing chamber, substantially as set forth.

3. The combination with a firing kiln having a firing chamber with a perforated arch covering the same, of a system of pipes positioned above said arch in the exit to the chimney stack of said firing chamber, and means for directing a heat-conveying medium through said system of pipes, substantially as set forth. 65

4. The combination with a combustion chamber in apparatus of the general class described, of a system of pipes positioned adjacent to said combustion chamber intermediate of its chimney stack, two headers connected respectively with a plurality of inlets and exits to and from said system of pipes, said exits connecting with the air supply for said chamber and with an external chamber, and means associated with the inlet header for supplying a heat-conveying medium thereto and through said system of pipes to the exit header thereof, substantially as set forth. 70 75 80

5. The combination with a combustion chamber in apparatus of the general class described, of a plurality of fire places peripherally disposed about the lower portion of said chamber, a system of pipes positioned in the upper portion of said chamber, intermediate means for protecting said pipes, two headers connected respectively with a plurality of inlets and exits to and from said system of pipes, means for supplying air to the inlet header, and connections from the exit header to the several fire places, substantially as set forth. 85 90 95

6. The combination with a plurality of associated combustion chambers, of a system of pipes positioned in each to encounter the waste heat, means for directing a heat-conveying medium through any of said pipes, and mains connecting said combustion chambers, whereby the heat-conveying medium may be directed to any associated combustion chamber to support combustion and aid in heating it, substantially as set forth. 100 105

7. The combination with a combustion chamber, of a heat-conveying system associated with its exit flue, a perforated arch positioned below said flue, a second chamber adapted to be partially heated by said system, and means for circulating a heat-conveying medium from said combustion chamber to the second-named chamber, whereby excess or waste heat may be conserved, substantially as set forth. 110 115

In testimony whereof I do now affix my signature.

FRANK MUNHOLLON.
